UNITED STATES PATENT OFFICE.

JOSEPH G. OSGOOD AND FRANK W. BACHMAN, OF CINCINNATI, OHIO, ASSIGNEES TO
SAID OSGOOD, TRUSTEE.

POWER-PLANE.

1,172,828.

Specification of Letters Patent. Patented Feb. 22, 1916.

Application filed October 12, 1914, Serial No. 866,394. Renewed July 15, 1915. Serial No. 40,123.

To all whom it may concern:

Be it known that we, JOSEPH G. OSGOOD and FRANK W. BACHMAN, both citizens of the United States, both residing at the city 5 of Cincinnati, in the county of Hamilton and State of Ohio, have invented certain new and useful Improvements in Power-Planes, of which the following is a specification.

10 Our invention belongs to that class of "power planes" which are hand operated. One man can operate the plane efficiently and do the work accurately and effectively.

Our invention is cheap of manufacture, 15 simple in construction and highly efficient in use, and it consists essentially in a base plate or supporting bed, carrying a cutter, a motor, adjusting means for the cutter, and connecting parts, and handles.

20 Our new power plane is used in leveling or releveling, cutting or die blocks of all kinds, floors, tables, bars, fixtures or any other surface needing leveling, or an even, smooth and uninterrupted surface.

25 Inasmuch as woods are of different hardness and tenacity, blocks made up of endwise maple pieces, others with woods of various grains, we find it necessary to use different cutters, made so as to be specially 30 applicable for the different kinds of leveling to be done; as for example soft wood can be cut with any ordinary cutter as shown in the plane, an endwise maple block would need a rasp or toothed bar, and still 35 other woods, other forms of cutters.

The cutters we employ are preferably circular or cylindrical in contour and are made with blades, burs, rasping surfaces or the equivalents thereof, so that the surface operated upon is cut or rasped off leaving a uniform and smooth surface.

40 In the accompanying drawing forming part of this specification, Figure 1, is a plan view of our new plane, Fig. 2, is a side view of one side of the plane, Fig. 3, is a longitudinal section of the plane, taken at line 3-3 of Fig. 1; Fig. 4, is a side view of the plane, being the opposite side to the one shown in Fig. 2, and Fig. 5, is a detailed partly sectioned, broken away view of details for raising and lowering the cutter, on line 5-5 Fig. 1.

The bed plate or base of the plane is 45 preferably made of a casting having a bottom 1 and sides 2-2, the bottom hav-

ing a slot 3. This bed plate may be made of any material and be of any desirable shape or contour. On the bottom 1, we connect at points 4 (see Fig. 3), a motor 5 of any approved form or construction. Power 60 can be transmitted to the motor in any of the ordinary ways, as through electric wires, not shown; any other motive power may, however, be used to operate the motor. The motor 5 has a shaft 6, at one end of 65 which is carried a gear wheel 7, which meshes with a large gear 8 on shaft 10, which in turn meshes with a gear 9, on shaft 12, at one end of the cutter 13. The cutter 13 is, at each side, formed into a short 70 shaft like end 12. The cutter works in the slot 3 in the plane bottom and can be lowered or raised to make cuts of varying depths on the surface on which it is operating.

75 We will now describe the mechanism for raising and lowering the cutter to enable it to make cuts of varying depths. We provide a yoke 15 carrying at each side at its ends an eccentric bushing or journal 16, 80 keyed thereto by key 17. The eccentric bushes 16 are supported or journaled in boxing 18 of any suitable form and the shaft 12 of cutter 13 is eccentrically journaled in the bushings 16. In the bottom 1, at point 85 20 we rigidly connect a screw 21. On the yoke 15 we provide short rearwardly extending arms 22-22. A thumb nut 23 works up and down on the screw 21. This nut 23 has a circular slot or groove 19 into 90 which the pins 24-24 extend, so that when the nut 23 is screwed down, the pins will move down with the said nut 23 and when the nut is screwed up, the pins will move up with said nut, thus lowering or raising 95 the nut 23, also lowers or raises the pins 24-24 with it and the pins being connected to the arms 22-22 lower or raise them, and they being made integral with the yoke 15,

100 which at its extended ends carries the eccentric bushings 16, turns said bushings in the journal boxes 18, thus also carrying the cutter 13, which is journaled in said bushings, around with said eccentric bushings, thus varying the eccentric point, where 105 shaft 12 is journaled in said bushings, away from or toward the slot 3 in the bed plate 1 and consequently brings the cutter 13 away from or farther down in the said slot to make a cut of less or greater depth. At 110

the front of the frame we provide standards 25, in which we journal a cross rod 26, which is made as a hold or handle, and at the rear of the frame 1 we connect a handle 27 of any approved form. It is thus constructed, when the device is used as a hand plane where the work is readily accessible, but in case the work is better done at a distance, we provide a handle 28, which we connect to the motor casing in any approved way, (see Fig. 4).

The knives on the cutter are marked 30. These knives may be of any form or size and arranged around the cutter 13 in any desirable manner. We may use a rasp, a burred bar or sanding tool in place of cutter 13, and may use it for any kind of work, cutters of varying contour being employed for different kinds of work for which they 20 are best fitted.

What we claim as new and our invention and desire to secure by Letters Patent is:

In a plane of the character described, a bed plate provided with a slot and with outer side walls, a circular cutter operating in said slot, a yoke provided at each side with bushings journaled in said walls over said slot, the circular cutter being journaled eccentrically in the said bushings between their axis and said slot, and means connected 25 with the yoke for oscillating the said bushings, carrying the circular cutter with them, to raise and lower the latter.

Executed at Cincinnati, Hamilton county, Ohio, this 9th day of October, 1914.

JOSEPH G. OSGOOD.
FRANK W. BACHMAN.
